(57) **CLAIM**

The ornamental design for a headset earpad, as shown and described.

DESCRIPTION

FIG. 1 is a perspective view of headset earpad showing the new design;

FIG. 2 is a front view thereof;

FIG. 3 is a rear view thereof;

FIG. 4 is a left side view thereof;

FIG. 5 is right side view thereof;

FIG. 6 is a top plan view thereof;

FIG. 7 is a bottom view thereof; and,

FIG. 8 is a front view thereof in an alternate position.

The broken lines depict portions of the headset earpad that form no part of the claimed design.

1 Claim, 8 Drawing Sheets
